UNITED STATES PATENT OFFICE.

JOHN A. KNIGHT, OF AUBURN, MAINE.

IMPROVEMENT IN COMBINED DRAWERS AND FOLDING DESKS.

Specification forming part of Letters Patent No. 158,421, dated January 5, 1875; application filed March 23, 1874.

To all whom it may concern:

Be it known that I, JOHN ADAMS KNIGHT, of Auburn, in the county of Androscoggin and State of Maine, have invented a new and Improved Portable Folding Desk-Surface, of which the following is a specification, reference being had to the accompanying drawings, in which—

Figure 1 is a view of my desk surface attached to an ordinary drawer, and extended, showing both the front and back of the same. Fig. 2 is a view of the same when rolled up and placed in the drawer. Fig. 3 is a view of the extension-frame when folded so as to allow the desk-surface to be rolled up.

The object of the invention is the production of a portable desk-surface that can be affixed to an ordinary drawer, and which can be readily folded and rolled into a small compass.

The desk-surface A is formed by gluing or otherwise fastening thin narrow strips of wood onto cloth or other suitable flexible material, which will allow it to be rolled into a small compass. The upper or outer edge has a ledge fastened to its under or cloth side, as shown at B, and the lower or inner edge is fastened to the folding frame C. This folding frame C has arms D D hinged to its inner

edge, as shown at E. By extending these arms so that the ends of them come in contact with ledge B, the desk-surface becomes rigid and ready for use by simply resting the under side of the frame on the edge of the table, as shown in Fig. 1. By folding the frame, as shown in Fig. 3, the desk-surface can be rolled into a very compact form, as shown in Fig. 2, occupying but a small space in the drawer. The frame C, being hinged at its inner edge by means of the pins f f, working in brackets g g, which are fastened to the drawer, can be elevated to any required degree, as shown in Fig. 1.

I claim as my invention and desire to secure by Letters Patent—

A drawer, provided with brackets g g, in combination with the flexible desk-surface A and folding arms D D, by means of which the desk-surface may be made rigid when said arms are extended, or flexible and capable of being rolled into a narrow compass when the folding arms are closed, substantially as described, and for the purpose set forth.

JOHN ADAMS KNIGHT.
